(57) **CLAIM**

The ornamental design for a condenser heat exchanger plate, substantially as shown and described.

DESCRIPTION

FIG. 1 shows a perspective view of a Design of a condenser heat exchange plate.

FIG. 2 shows a rear view of the Design.

FIG. 3 shows a front view of the Design.

FIG. 4 shows a left side view of the Design.

FIG. 5 shows a right side view of the Design.

FIG. 6 shows a top view of the Design.

FIG. 7 shows a bottom view of the Design.

FIG. 8 shows a cross-sectional view along line 8-8 of FIG. 3.

FIG. 9 shows a cross-sectional view along line 9-9 of FIG. 3.

FIG. 10 shows a cross-sectional view along line 10-10 of FIG. 3.

FIG. 11 shows a cross-sectional view along line 11-11 of FIG. 3.

FIG. 12 shows an enlarged view of a portion of the right side of the Design corresponding to the brace 12 of FIG. 3.

FIG. 13 shows an enlarged view of a portion of the right side of the Design corresponding to the brace 13 of FIG. 3.

FIG. 14 shows an enlarged view of a portion of the right side of the Design corresponding to the brace 14 of FIG. 3.

FIG. 15 shows an enlarged view of a portion of the right side of the Design corresponding to the brace 15 of FIG. 3.

FIG. 16 shows an enlarged view of a portion of the left side of the Design corresponding to the brace 16 of FIG. 3.

FIG. 17 shows an enlarged view of a portion of the left side of the Design corresponding to the brace 17 of FIG. 3.

FIG. 18 shows an enlarged view of a portion of the left side of the Design corresponding to the brace 18 of FIG. 3.

FIG. 19 shows an enlarged view of a portion of the left side of the Design corresponding to the brace 19 of FIG. 3.

FIG. 20 shows an enlarged view of the top of the Design corresponding to the brace 20 of FIG. 3.

FIG. 21 shows an enlarged view of the bottom of the Design corresponding to the brace 21 of FIG. 3; and,

FIG. 22 shows a cross-sectional view along line 22-22 of FIG. 1.

1 Claim, 9 Drawing Sheets
